UNITED STATES PATENT OFFICE.

ISADORE J. POLACK, OF CHICAGO, ILLINOIS.

WINDOW FRAME AND SASHES THEREFOR.

Application filed February 4, 1924. Serial No. 690,424.

To all whom it may concern:

Be it known that I, ISADORE J. POLACK, a citizen of the United States, and a resident of Chicago, county of Cook, and State of Illinois, have invented certain new and useful Improvements in and for Window Frames and Sashes Therefor, of which the following is a specification.

This invention relates to improvements in windows for buildings and has for its particular object to provide a structure of this character which presents simple and efficient means for swinging the window-sashes inwardly for purposes of cleansing, repair or the like, and which is generally, in all other respects, except as hereinafter particularly set forth, of standard construction and mode of operation.

A further object of the invention is to provide means whereby existing windows may be easily, quickly and cheaply converted to operate in accordance with this invention, the latter being directed more especially to the production of the hardware necessary to effect such conversion of old and new windows, capable of being installed by any carpenter or other skilled person.

The invention comprehends means for preserving the window-pane areas, the normal weather-tightness of the windows, greater ease of operation of the sashes for ventilating purposes, and permitting the use of the ordinary window-screens, drapery fixtures and the like as in the case of the windows most commonly found in present day buildings.

The preferred embodiment of the invention is illustrated in the accompanying drawings, in which:

Fig. 1 is a view in elevation, seen from the interior of a building, of a window constructed in accordance with the invention, part of the same being broken away and parts shown in section.

Fig. 2 is a section on the line 2—2 of Fig. 1, the window-sashes being omitted.

Fig. 3 is a vertical section on the line 3—3 of Fig. 4.

Figs. 4 and 5 are plan sections on the line 4—4 of Fig. 1, showing the sashes in normal and in swung-in positions, respectively.

Fig. 6 is a plan section on the line 6—6 of Fig. 1.

Fig. 7 is a perspective view of a hinge 55 employed.

The desirability of having windows so constructed as to permit the sashes thereof to be swung into the room for purposes of cleansing, has long been recognized and many attempts have been heretofore made to solve this problem satisfactorily, but, so far as I am informed no solution meeting with approval of architects and builders has heretofore been found. The solutions offered have been lacking in some very essential respect, as, for example, simplicity of construction or operation, or both; weather-tightness; cutting down window-pane area; preventing the use of the ordinary window-screens, draping fixtures and other hardware of standard type; freakish appearance; prohibitive cost, etc.

The present invention is directed to the provision of all the advantages incident to 75 swinging the window-sashes inwardly for cleansing, without sacrifice of any of the recognized meritorious features incident to present day construction, and to the accomplishment of this object at low cost and in a 80 very simple manner.

Practically, every planing mill in the United States produces the standard type of window-casings and sashes therefor, so that any departure from that standard construction would necessarily be accomplished only at excessive cost and in the face of the antagonism of manufacturers, architects, builders and mechanics engaged in building trades, despite the economic advantages resulting from the factors of personal safety and time savings effected.

My invention permits the use of the standard type of window-casing A and window-sashes B and C, the casing A being modified only with respect to removal or elimination of some stops or sash-guides, in rendering one of the latter removable, and rendering another thereof pivotally movable.

The casing A includes the sash-weight 100 wells 1 and 2, the sheaves 3 and 4 for the sash-cords, which, in the case of my invention, are necessary only at one side of the casing. It also includes the inner stop-strip

5, rigidly mounted on one side of the casing; the similar hinged stop-strip 6 at the other side thereof; and the stops 7 and 8. The present day construction of top and sill portions remains unchanged.

Mounted upon one side-wall of said casing A and extending vertically from the sill to a point just below the sheaves 3 for the sash-cords, are two parallel channel-strips 9 and 10, the former having one side-flange abutting against the edge of the stop-strip 8, and the channel 10 being spaced from the channel 9, a distance equal to the width of the usual stop or guide 7 normally provided between the strip 5 and the outer stop 8. Openings are provided in the middle or web-portion of each channel, 9 and 10, for the reception of screws or other fastening means 11.

20 The side-flanges of the channels 9 and 10 are provided with opposed edge-flanges 12 to thereby choke the mouth-portions of said channels and provide guide-rails for the leaves 13 of the hinges for the upper sash 25 B and the leaves 14 of the hinges for the lower sash C, said leaves 13 and 14 being substantially similarly constructed. Each thereof is provided along one edge with the sleeves 15 for the hinge-pin 16 and, on one face with parallel L-shaped flanges 17 and 18, the free portions of which are spaced from the leaf a distance substantially equal to the thickness of the flanges 12 of the channels. Disposed on the inner opposed faces of said flanges 17 and 18 are projections 19 in which the pivot-pin for the anti-friction roller 20 is mounted, there being an opening 21 in the leaf to accommodate said roller 20.

40 The said leaf is adapted for engagement with a channel by inserting the roller and free portions of the L-shaped flanges 17 and 18 into one end of the channel for same either before or after the latter is mounted 45 on the casing A. Thus the roller 20 rides upon the middle or web-portion of the channel and the free portions of the L-shaped flanges ride upon the inner faces of the flanges 12.

50 The channels are very shallow so as to require the side edge of the window-sash to be cut off to an extent less than the depth of the stops 7 and 8.

55 The leaves 15 for the hinges of the lower sash are associated with leaves 22 secured and set into the side-edge of the sash a depth sufficient to also receive the leaf 15, the pivot portions thereof being provided with flat faces to become flush with the inner face of the sash, in order to present a neat appearance.

60 The leaves 15 for the hinges of the upper sash differ from the leaves 15 for the hinges of the lower sash, in that they are provided, each, with an edge flange

23 at the free end of which are the pivot sleeves for the pivot-pin. These hinges are of the three-leaf type and include the L-shaped leaf 24 pivotally associated at one end with the leaf 15 and at the other end 70 with the plane or flat leaf 25 which is secured to the sash, the latter being recessed a depth sufficient to receive the leaves 15, 24 and 25, and also to receive the outwardly projecting portions of the leaves 15 and 24, 75 it being very desirable that no parts of the hinges project beyond the front and rear faces of the sash for purposes of neatness of appearance and in order that the stops 7 and 8 may be retained.

80 In swinging the upper sash into the room, it first turns on the pivot between the leaves 24 and 25 through an arc of about forty-five degrees. Then the leaves 24 are swung through an arc of about ninety degrees relatively to the leaves 13 with which they are associated and the sash A may then be further swung until its total arcuate movement has aggregated about ninety degrees. The outward projection for the flanges 23 of the leaves 13 of the hinges for the upper sash, obviously throws the side edge of the upper sash, when turned to its last-named position, outwardly from the plane of the leaves 13 a distance greater than the thickness of the 95 sash, this being obviously advantageous in that it permits the upper sash to be turned to extend perpendicularly to its normal position similarly to the lower sash as shown in Fig. 5.

100 As shown in Fig. 1, only a little more than one-half of the stop 6 is hinged to the casing along its outer edge, it being necessary to raise the lower sash C, to clear the sill, before it can be swung to the position shown in Fig. 5. The stop 7 includes a removable portion which is removably mounted in the casing, the removable portion being that which extends from the sill to about the height of the hinged portion of the strip 6.

110 It is fitted at its lower end into the pocket 27 in the sill and is further held in place by the shoulders at the ends of the beveled meeting faces of the top rail of the lower sash and the bottom rail of the upper sash, said shoulder of the top rail of the lower sash being shown at 31 in Fig. 6, the dotted line 32 of the latter indicating the corner at the inner edge of the bottom face of the bottom rail of the upper sash. It will be noted that there is clearance between the shoulder 32 and the stop 7, such clearance being also provided between said stop 7 and the similar shoulder 115 (31) of the bottom rail of the upper sash. In order to remove the removable portion of the stop 7, the lower sash is first swung into the room and the upper sash lowered until its bottom rail is just above the window sill. The upper end of said removable portion of the stop 7 may then, because of the

100

130

aforesaid clearance, be swung out of its groove until its upper end clears the lower end of the fixed portion of the stop 7 and is then lifted clear of the pocket 27 and bottom rail of the upper sash.

On opposite sides of this removable stop 26 are mounted two flat metal strips 29 extending from the sill to the same height as the channels. The side edges of the sashes 10 opposing said strips are beveled off, as shown in Fig. 4, in order to permit said sashes to swing on their pivotal axes. Anti-friction roller carrying fixtures, which include the rollers 30, are mounted in recesses in said 15 beveled edges of the sashes at about the same elevations as the hinges at the other edges thereof, said rollers riding on the strips 29 and coacting with the hinge-rollers to cause the sashes to be easily raised and 20 lowered to prevent binding of said sashes due to hinge-sag.

Preferably only one sash-weight is provided for each sash and the cords thereof attached to the hinged edge portions thereof 25 and trained over the sheaves 3 above the upper ends of the channels. Thus the sheave fixtures for the other side of the window-casing may be omitted and a saving effected.

In order to swing the upper sash into the 30 room, it must be lowered to the same position as the lower sash, and the stop 26 removed.

It will be noted that the channels and 35 hinges may be interchangeably associated with either side of the window-casing, this being very advantageous from the manufacturing and installation standpoints.

Inasmuch as window frames and the sashes therefor are manufactured in standard sizes as to thickness of side rails of 40 sashes and corresponding width of guide grooves therefor, the channels can be made in widths to fit the latter and the hinges to fit the sashes, the construction allowing 45 for sufficient tolerance to obviate close and accurate fitting during installation. The latter is thus rendered so simple that persons other than skilled mechanics may effect the same with ease, using only an ordinary plane 50 and a chisel for the purpose.

It will further be noted that, aside from the removal of the stop 7 at one side of an ordinary window frame and the small amount of labor required to cut the same to 55 provide the removable portion and then replace the upper portion permanently and leave the lower portion removable, and that of removing, cutting and replacing the inner stop or turn, all labor is confined to the 60 sashes.

I claim as my invention:

1. In a window, a frame, upper and lower sashes slidably mounted therein and pivotally mounted at one side to permit of the 65 swinging thereof to open position, the other

sides of said sashes being bevelled to permit close fitting of the sashes in the frame and to overcome binding thereof when the sashes are swung to open and closed positions, a set of superposed hinges secured to the non-bevelled side of each sash and providing pivots for the sashes, one set of the hinges provided with a pair of oppositely disposed L-shaped flanges, and means fixed to the frame and overlapping said flanges for slidably securing the hinges to the frame.

2. In a window, a frame, a slidable sash mounted therein, a three-leaf hinge having one leaf thereof slidably engaged with the frame and another leaf thereof secured to a side edge of the sash, and an intermediate leaf pivotally secured at opposite edges to the respective first-named leaves, the said intermediate leaf and the leaf slidably engaged with the frame being each L-shaped and providing flanges disposed on the outer or weather face of the sash.

3. In a window, a frame, a slidable sash mounted therein, a three-leaf hinge having one leaf thereof slidably engaged with the frame and another leaf thereof secured to a side edge of the sash, and an intermediate leaf pivotally secured at opposite edges to the respective first-named leaves, the said intermediate leaf and the leaf slidably engaged with the frame being each L-shaped and providing flanges disposed on the outer or weather face of the sash, the several hinge pivots being disposed between the inner face and the outer or weather face of the sash.

4. In a window, a frame, a slidable sash mounted therein, a three-leaf hinge having one leaf thereof slidably engaged with the frame and another leaf thereof secured to a side edge of the sash, and an intermediate leaf pivotally secured at opposite edges to the respective first-named leaves, the said intermediate leaf and the leaf slidably engaged with the frame being each L-shaped and providing flanges disposed on the outer or weather face of the sash, the several hinge pivots being disposed between the inner face and the outer or weather face of the sash, said flanges and the several hinge pivots being disposed between the inner and outer faces of the sash with the outer face of the flange of the leaf slidably connected with the frame disposed substantially flush with the outer face of the sash.

5. A window frame comprising a frame, upper and lower sashes mounted therein, a channel-shaped guide member for each sash, said members fixedly secured to the frame and formed with a pair of spaced opposed flanges, hinge elements carried by one side of each of said sashes, and provided with L-shaped flanges overlapping the flanges of a guide member for slidably coupling the sashes thereto, said sashes having their other sides slightly bevelled to prevent binding.

when the sashes are swung to open and closed position on said elements, metallic strips secured to the frame and engaged by a portion of the bevelled sides of the sashes when these latter are swung to closed position within the frame, the hinge elements for one of said sashes including two leaves,

each having an outwardly extending flange along one side edge and pivotally connected at the outer edges of said flanges.

In testimony whereof, I have hereunto set my hand, this 28th day of January, 1924.

ISADORE J. POLACK.
